UNITED STATES PATENT OFFICE.

WILLIAM E. HEWIT, OF DAVID CITY, NEBRASKA.

DESIGN FOR A GROCER'S CABINET.

SPECIFICATION forming part of Design No. 28,938, dated June 28, 1898.

Application filed May 24, 1898. Serial No. 681,644. Term of patent 7 years.

To all whom it may concern:

Be it known that I, WILLIAM E. HEWIT, a citizen of the United States, residing at David City, in the county of Butler and State of Nebraska, have invented a new and original Design for Grocers' Cabinets, of which the following is a specification.

My invention relates to designs in grocers' cabinets, of which the accompanying drawing is a perspective view of a cabinet embodying my design.

The cabinet consists of an upright hexagonal case having a top B with a central opening C, the lower edge provided with panels D. Projecting upward from the bottom and to

the top between the panels are the corner-stands E, and between these corner-stands and the top and the panels are the panels G, as illustrated.

Having thus described my invention, what I desire to secure by Letters Patent is—

The design for a grocer's cabinet substantially as herein shown and described.

In testimony whereof I have hereunto set my hand in the presence of two subscribing witnesses.

WILLIAM E. HEWIT.

Witnesses:

HARVEY DAVIS,
W. S. ROSENSTOCK.
